CARRYING CASE

Arthur J. Bradford, Wilmette, Ill., assignor to
Motion Picture Engineering Corporation, a corporation of Illinois

Application August 9, 1946, Serial No. 689,364

4 Claims. (Cl. 45—68.2)

1

This invention relates to carrying cases in general and more particularly to carrying cases which may be utilized for carrying articles such as projection machines and the like.

The principal object of this invention is to provide an improved carrying case which is rigid and strong in construction, which is light in weight, which is convenient to handle and which is readily and inexpensively assembled.

In accordance with this invention the carrying case is formed from a pair of end pieces, a housing piece, and a bottom piece. The end pieces may be provided around their top and sides with marginal grooves and end flanges on the housing piece may fit into the marginal grooves to fit the pieces together. Bottom double flanges may be provided on the housing piece to add strength thereto and the bottom flanges may enter opposed recesses in the end pieces to lock the pieces together. The bottom piece may be secured against the end pieces and the housing piece by clasps secured to the bottom piece and the end pieces and the carrying case may be carried by a handle on the top of the housing piece. The articles to be carried may be secured, if desired, to the bottom piece.

Further objects of this invention reside in the details of construction of the component parts of the carrying case and the cooperative relation between the component parts.

Other objects and advantages will become apparent to those skilled in the art upon reference to the accompanying specification, claims, and drawing, in which—

Fig. 1 is a top plan view of the carrying case;

Fig. 2 is a side elevational view thereof;

Fig. 3 is an end elevational view thereof;

Fig. 4 is a partial enlarged sectional view taken substantially along the line 4—4 of Fig. 2;

Fig. 5 is an enlarged partial perspective view showing the cooperation between one side of the housing piece and an end piece;

Figs. 6 and 7 are enlarged partial perspective views showing the cooperation between the other side of the housing piece and an end piece.

The carrying case includes a pair of end pieces 10 and 11 preferably made of wood, plastic, or other suitable, light weight material, a housing piece 12, preferably made of sheet material such as sheet metal or sheet plastic or the like, and a bottom piece 13, preferably made of wood, plastic or other similar material. The bottom piece 13 may be provided with suitable legs or supports 14.

The top and side edges of the end pieces 10 and 11 are provided with marginal grooves 16 for receiving flanges 17 formed on the housing piece 12. Thus the housing piece 12, forming the top and sides of the carrying case, fits the end pieces 10 through the flange and groove con-

2

nection whereby longitudinal movement of the end pieces 10 and 11 with respect to the housing piece 12 is prevented.

Each of the end pieces 10 and 11 is provided with opposed recesses 19 and 20 at the bottom thereof. A continuous double flange is provided at the bottom of one side of the housing piece 12 and this double flange includes a horizontal portion 21 and a vertical portion 22. The horizontal portion 21 of the double flange engages the bottom of the end pieces 10 and 11 and the vertical portion 22 engages within the recesses 19 of the end pieces 10 and 11. The horizontal portion 21 of the double flange in engaging the bottom of the end pieces 10 and 11 prevents the housing member from being lifted upwardly with respect to the end pieces 10 and 11 and the vertical portion 22 engaging within the recesses 19 prevents the lower portion of the housing piece 12 from moving outwardly with respect to the end pieces 10.

The other side of the housing piece 12 is provided with a double flange contained between the end pieces 10 and 11. This double flange includes a horizontal portion 23 and a vertical portion 24. This same side of the housing piece 12 is provided with a pair of ears 25 at the end pieces 10 and 11 and these ears are, in the process of assembly, bent around the bottom of the end pieces 10 and 11 and into the recesses 20, as shown in Figs. 6 and 7 so that the ears 25, after bending in the assembly, form continuations of the double bottom flange.

In assembling the housing piece 12 and the end pieces 10 and 11, the vertical portions 22 of the double flange along one side of the housing piece 12, are inserted in the recesses 19 and the flanges 16 are inserted in the grooves 17. The double flange on the other side of the housing piece 12 then lines up with the bottoms of the end pieces 10 and 11 with the ears 25 depending, as shown in Fig. 6. The ears 25 are then bent up into the recesses 20, as shown in Fig. 7, and as a result the housing piece 12 is securely locked to the end pieces 10 and 11. The double flanges on either side of the housing piece 12, in addition to assisting in locking the pieces together, also adds strength and rigidity to the housing piece 12.

The bottom piece 13 may be secured against the end pieces 10 and 11 and the housing piece 12 by suitable clasps 27, one portion of which is secured to the bottom piece 13 and the other portion to the end pieces 10 and 11. As shown, the bottom piece 13 may have a substantially flat marginal portion, end parts of which are abutted by the lower edges of the end walls, which are shown as straight, and side parts of which are abutted by the first or horizontal flange 23. It will be seen that in effect each side

of the housing piece 12 terminates in a U-shaped structure, an arm of which, formed by the outer reach of the housing piece 12, contacts an outer side edge of each of the two end walls, a web of which contacts limited portions of the lower straight edges of the end walls adjacent such side edge, while a second arm, formed by the second or vertical flange portion 24 or the ear part 25 thereof, enters the recesses in the two end walls and contacts the surfaces thereof that are toward but spaced inward from the side edges that the first arm contacts.

A handle 29 is carried by brackets 30 which, in turn, are suitably secured to the housing piece 12 by means such as rivets.

With the clasps 27 securing the end pieces 10 and 11 to the bottom piece 13, the carrying case may be carried by the handle 29. In order to gain access to the interior of the carrying case, the clasps 27 may be unclasped and the housing portion 12 and end pieces 10 and 11 lifted from the bottom piece 13. If desired, the articles to be carried within the carrying case, such as a projecting machine, may be secured to the bottom piece.

By reason of the above construction there is provided an improved carrying case which is rigid and strong in construction and yet light in weight, which is convenient to handle and manipulate, and which is readily and inexpensively assembled.

While the invention has been disclosed in connection with a particular style of carrying case, it may be readily utilized in other types of cases such as suitcases, wardrobe cases, trunks, etc., wherein both halves of such cases may be formed of pieces similar to the end pieces 10 and 11 and the housing piece 12, with both halves being suitably secured together by hinges, clasps, and the like.

While for purposes of illustration one form of this invention has been disclosed, other forms thereof may become apparent to those skilled in the art upon reference to this disclosure, and, therefore, this invention is to be limited only by the scope of the appended claims and prior art.

I claim as my invention:

1. In a carrying case, the combination of a pair of opposed end pieces, each provided around its top and sides with a marginal groove and each provided with facing recesses at the bottom, and a housing piece forming the top and sides and provided with end flanges fitting in the marginal groove and provided on one side with a continuous double bottom flange engaging the bottoms of the end pieces and entering opposed recesses and provided on the other side with a double bottom flange between the end pieces and with ears adjacent the end pieces engaging the bottoms of the end pieces and entering the recesses and forming continuations of the bottom flange.

2. In a carrying case element that has an open side, and that comprises a pair of end walls each having a groove extending around its edge on three sides, and a generally U-shaped housing piece extending between said end walls, and about said three sides and having at its end inturned flanges engaged in said grooves; a flange structure extending along each edge of said housing piece between the end walls and comprising a first portion extended generally inward and contacting a portion of the fourth sides of said end walls and a second portion extending from the inner margin of said first portion

in angular relation thereto and away from said fourth edge of each end wall and said first flange portion, each said end wall having adjacent but spaced inward from each of its side edges a recess into which said second portion is extended in contact with a lateral surface at the side of the recess toward the adjacent side edge of said end wall.

3. In a carrying case, a cover structure for attachment to and release from a closure piece that has a flat marginal portion, said cover structure comprising a pair of spaced end walls each having a straight edge for abutment with end parts of such marginal portion, and three other edges including opposite side edges and an intervening edge and about which three edges a groove extends, and a housing member having side and intervening reaches and provided at opposite ends with a flange engaged in said groove; an improved edge and interlocking arrangement of said housing member and end walls, comprising a flat first flange portion extended inward from each margin of said housing member for face to face contact with a side part of the marginal flat portion of the closure piece, a second flange portion extending angularly from the inner margin of each said first flange portion, each said end wall being provided adjacent each end of its said straight edge with a recess extending from said straight edge and spaced from the adjacent side edge by structure having a surface that is in contact with the part of said second flange portion that is extended into said recess.

4. In a carrying case, a cover structure for attachment to and release from a closure piece having a flat marginal portion, said cover structure comprising a pair of spaced end walls each having a straight edge for abutment with end parts of such marginal portion, and three other edges including opposite side edges and an intervening edge and about which three edges extends a groove, and a housing member having side and intervening reaches and provided at opposite ends with flanges engaged in said grooves; an improved edge and interlocking arrangement of said housing member and end walls, comprising a generally U-shaped structure at each lateral margin of said housing piece, 50 such structure comprising an arm contacting a side edge of each end wall, a web contacting a part of said straight edge of each end wall, and a second arm having each of its ends entered into a recess that has a surface spaced inward from the side edge of the end wall that is contacted by said first arm and that extends from said straight edge, said second arm contacting said surface.

ARTHUR J. BRADFORD.
